UNITED STATES PATENT OFFICE.

MATTHEW J. DAVIS, OF PORTLAND, OREGON.

LOG RAFT.

Application filed December 1, 1924. Serial No. 753,339.

My invention relates to improvements in logs rafts, the objects of the invention being amongst other things, to provide means for binding the raft together that the logs forming the floor layer of the raft may be released when certain bindings or ties are loosened, to provide for the main bindings being fastened to a centre stick so that as the raft is broken up, such ties may be reclaimed from one log only, and further to provide means for preventing the endwise movement of the upper layers of logs adjacent the ends of the raft.

The invention consists essentially of a floor layer of logs laid side by side and bound together by pairs of transversely disposed lines extending from the centre stick to the boom stick, the pairs of lines being fastened together at the boom sticks, and a plurality of layers of logs superimposed upon the floor layer and bound thereto, as will be more fully described in the following specification, in which:—

Fig. 1 is a transverse section of the floor layer showing the manner in which the logs thereof are bound together.

Fig. 2 is a transverse section of the floor layer showing the disposition of the fastening of the binding ropes after the floor has been submerged by the superimposed load of logs.

Fig. 3 is a transverse view showing the end bindings of the raft.

Figs. 4 and 5 are transverse sections showing the manner in which the overties are connected to the raft floor.

Fig. 6 is a part elevational and part sectional longitudinal view of the raft.

Fig. 7 is a view showing a method of binding logs end to end.

Fig. 8 is a view showing the method of shortening the distance between adjacent log ends which had been previously bound together.

Fig. 9 is a view showing the means of binding the ropes connecting the ends of the side booms preparatory to removing the rope clamps.

Fig. 10 is a detail view showing the method of applying the binding to said ropes.

In the drawings like characters of reference indicate corresponding parts in each figure.

With a view to showing more particularly the path of the several binding lines, the

lines of one series in Figures 1, 2 and 3 are shown in a manner distinctive to the lines of the other series, and further, while several lines of each series will be used throughout the structure, but few are illustrated in order that their showing may be more clearly defined.

The numeral 1 indicates a centre stick which may be formed of a plurality of logs arranged end to end and connected together by chains or other suitable means, and extending for the length of the raft. 2 are logs or rows of logs arranged side by side forming the floor of the raft. When the raft is made of more than one log length, 70 the logs forming the floor particularly are so arranged that the ends of the logs in one row extend beyond or fall short of the ends of the logs in the adjoining rows, in order to provide for longitudinal stability of the 75 raft when completed.

The numeral 3 indicates a pair of side booms, which are formed with one or more rows of logs butted end to end and connected together. Some of the floor logs at 80 each end of the raft, indicated by the numeral 4 see Figures 3 and 6 are arranged to project beyond the ends of the raft for reasons which will be explained later. Connected to the centre stick 1 are pairs of lines 5 which extend therefrom in opposite directions, first passing over the logs forming the floor until the side boom 3 is reached, where the general lay of the line is reversed, bringing it underneath the side boom as 85 shown in Figures 1, 2 and 3. A pair of lines 6 (shown with diagonal hatching) are also connected to the centre stick 1 and are passed in opposite directions therefrom under the floor logs, until the side booms are 90 reached, each then being drawn up and passed thereover and then tightly clamped upon its corresponding line 5 as at 7. (Fig. 1) adjacent the waterline of the raft floor as thus formed. Some of the inner ends 8 of the lines 5 and 6 are drawn up in pairs between the logs, as the load is imposed and are bound about the logs forming the central portion of the raft, such pairs of ropes do not necessarily encompass the same set 100 of logs throughout the raft, but are carried up in any position and are tightly fastened together over the load.

After the floor has been bound together, overtie lines 9 (shown in solid black line in 110

Figures 1, 2 and 3) which are attached primarily to the centre stick 1 are drawn up between the floor logs adjacent the side booms 3 and are laid out pending the loading of the raft.

The numeral 10 indicates a plurality of logs forming the superimposed load, and laid side by side and end to end, preferably with the abutting ends of one row of logs 10 at a distance from the abutting ends of the logs in adjoining rows, so as to add stability to the completed raft. A plurality of logs 11 (see Figures 3 and 6) are arranged to project beyond the ends of the raft for the purpose of providing a support for and means for securing end swifters 12 to the raft, such logs and swifters being bound together by lines 13 which prevent the lateral spreading of the ends of the raft and in consequence reduces the towing resistance of the raft.

The numeral 14 indicates the top tier of logs which is somewhat shorter in total length than the raft and is abutted at each 25 end with a log 15 laid transversely of the raft, and which is securely bound by vertical lines 16 extending downwards to the end swifters 12 and to the projecting ends of the logs 4 (see Figures 3 and 6). The transverse logs 15 are bound to each other by a plurality of longitudinally disposed lines 17 which are prevented from falling in between the logs forming the top layer by means of further transverse logs 18 underlying them.

The numeral 19 (see Figures 7 and 8) indicates a binding rope which is either bound around adjacent log ends, particularly in the raft floor and preferably in some of the other longitudinal rows of logs forming the 40 skin of the raft, or are passed through holes bored therein as desired, which line has an intervening connecting portion 20 running longitudinally from the end of one log to the end of the adjoining log so that in the event of its being necessary to shorten the spacing between the logs ends, one of the logs may be rolled to dispose the intervening portion 20 of the line 19 helically about the logs as shown in Figure 8. The logs rolled as above 45 described to shorten the end spacing are held against a return movement by their contact with other logs, furthermore the logs so bound prevent elongation of the bottom or sides of the raft and in consequence prevent 50 flexure of the raft body.

The numeral 21 (see Figure 5) indicates a plurality of overties which are carried under the raft and are brought up between the floor logs adjacent the side booms and 60 are, after the complete loading of the raft, carried over the raft, their free ends being looped around the side booms and being fastened by clamps, back upon themselves. When the overties 21 are temporarily secured, the free ends of the overties 9 are

carried over the raft and looped around a side boom, being then fastened upon themselves in a like manner.

Each overtie 21, when starting from the side of the raft, is first passed around a 70 floor log adjoining the side boom and fastened upon itself with a clamp (see Fig. 5), the free end is then passed over the side boom and brought up between it and the adjoining log, from thence the overtie is 75 passed inwards of the raft over such log and down, thence passing under the raft floor and around the raft in the manner above described. By connecting the overties in this manner, the tendency of overties to cut 80 into the logs and bind, is reduced to a minimum, permitting the ropes to run freely around the logs and become detached therefrom as soon as the binding clamps are removed.

The overties 9 and 21 are primarily tightened, then a further tightening is effected upon the lines 17, rendering the raft a composite mass of logs capable of withstanding the action of heavy seas without loss of logs 90 therefrom. Lines 22 are connected to the end of each centre stick and are carried up over the transverse logs 15 and are extended longitudinally of the raft and after tightening, are bound together at their point of 95 meeting, these lines are then connected at intervals to the overties 9 and 21. Longitudinal lines 23 are extended from one end of the raft to the other adjacent the side booms and are connected to the end swifters 100 12 (see Fig. 3) these lines are also clamped at intervals to the overties 9 and 21, so that the lines 22 and 23 and the overties 9 and 21 form a fabric by which the raft is bound as a whole to prevent its elongation, or its 105 distortion, during the towing in rough waters.

The numeral 24 (see Figs. 9 and 10) indicates a line which is passed around the ends of the side booms and their free ends clamped together as at 25, for the purpose of holding the ends of the raft from spreading when removing the fastening means of the several ropes during the breaking up of the raft at destination.

To prevent any tendency to elongation of the raft during towing, a pair of tow ropes 26 are connected to any suitable position in front of the raft and carried lengthwise thereof adjacent the side booms, and are then passed through a pair of dead eyes or blocks 27, secured to the after end and back along the side booms and through a ring bolt 28, the free ends being connected together for attachment to the ship's tow line.

Prior to releasing the clamps 25, the strands of the lines 29 are tightly bound together with a light line 30 woven first about one strand and then the other (see Figs. 9 and 10) when the clamps can be removed,

then when all other lines are freed at their bindings, the lines 29 are cut, allowing the side booms to spread apart, and the logs forming the raft to come to rest in the water.

5. What I claim as my invention is:

1. A log raft comprising a raft floor, and a superimposed load of logs upon the floor, means for binding the superimposed load of logs to the raft floor, transversely disposed 10 logs upon the ends of the raft and lines binding the ends of the raft floor to the transverse logs and lines extending longitudinally of the raft to bind the transverse logs together.
15. 2. In a log raft having a raft floor and a superimposed load of lengths of logs bound to the raft floor, of ropes extending along opposite sides of the raft, one end of each rope being fastened adjacent the forward end, the rope then extending to the rear end and passed through a dead eye or sheave and from thence being led back to the forward end passed through an eye with the end of the opposite side rope for connection to a tow rope.

3. In a log raft having a raft floor bounded by side booms and a superimposed load of logs upon the raft floor, of ropes connecting the ends of one of the side booms to the 30 ends of the other side booms, the ends of said ropes being fastened together by clamps, and means for temporarily binding the ends of the ropes together prior to the removal of the clamps and the dismantling of the 35 raft.

4. In a log raft having a raft floor bounded by side booms, and a superimposed load of logs upon the raft floor, of ropes con-

necting the ends of one of the side booms to the ends of the other side booms, the ends 40 of said ropes being fastened together by clamps, and means for temporarily binding the ends of the ropes together prior to the removal of the clamps and the dismantling 45 of the raft, said binding means comprising a light line capable of being easily severed, woven alternately around one rope and then around the other.

5. The method of dismantling a log raft in which the ends of the side booms are connected together by binding ropes extending from one side boom to another and the free ends of the ropes being brought together and clamped, which consists of binding the 50 strands of the ropes together with a light line to take the strain normally carried by the clamps, then removing the clamps and finally severing the light line to release the binding ropes and allow the raft to spread 55 apart.

6. In a log raft having a raft floor formed of logs and bounded by side booms, and a superimposed load of logs upon the raft floor and overtie ropes each having one end 60 passed around a floor log adjoining a side boom and fastened back upon itself with clamps, the rope being then passed around the side boom and between it and the adjoining log, thence being carried past such log 65 and under the floor of the raft and brought over the raft and its free end fastened to the side boom.

Dated at Portland, Oregon, this 14th day of October, 1924.

MATTHEW J. DAVIS.
